ELECTROMAGNETIC TRANSDUCER

Leslie Russell Ward, South Harrow, England,
assignor to Truvox Engineering Company Limited, Wembley, England, a British company

Application November 18, 1947, Serial No. 786,616
In Great Britain November 22, 1946

10 Claims. (Cl. 179—115.5)

1 This invention relates to electrodynamic loudspeakers or microphones of the moving-coil type, i. e. of the type comprising a coil-winding suspended for movement in a magnetic field and connected with a sound diaphragm, said diaphragm being caused to vibrate to produce sound waves by the passage of oscillatory currents through said coil-winding or, conversely, being vibrated by sound waves to cause the generation of oscillatory currents in said coil-winding.

The conventional loudspeakers and microphones of this type usually comprise a magnetic structure including either a permanent- or an electro-magnet consisting of several stamped or cast ferromagnetic members defining an annular magnetic flux-gap in which the above mentioned coil-winding is arranged to operate. The sound diaphragm is usually arranged outside the magnetic structure and is supported in a separate chassis or equivalent supporting element having an annular rim to which the periphery of the sound diaphragm is secured. Such conventional arrangements necessarily have a considerable depth or thickness dimension, the latter being at least equal to the combined thicknesses of the chassis element and the magnetic structure. Furthermore such conventional constructions frequently possess a relatively strong magnetic leakage field therearound; this leakage field may cause serious interference with other associated apparatus, for instance, a cathode ray tube in a television receiver.

The object of the present invention is to provide an improved simplified construction for a moving-coil microphone or loudspeaker in which a greatly reduced depth or thickness dimension is needed and in which the external magnetic leakage field is materially reduced or even substantially eliminated.

According to the invention the magnetic structure is arranged to serve also as the sound diaphragm supporting chassis and comprises a first member of sheet ferromagnetic material shaped to an arched or cup form, a second member of similar sheet ferromagnetic material adapted to span the arch or cup mouth of said first member and a permanent magnet of solid bar form secured at one end to the inner face of said second member and arranged so as to project at its opposite end into an aperture in the centre of said first member so as to define, in conjunction with said aperture, a magnetic flux-gap for a coil winding carried by the sound diaphragm which is housed between the two members and

2 is secured around its periphery to at least one of said members.

Each of the two members is conveniently constituted by a stamping or pressing while the permanent magnet is preferably in the form of a short cylindrical bar or rod secured in place at one end only.

In order that the above and other features of the invention may be more readily understood 10 several embodiments thereof will now be described with reference to the accompanying drawings in which—

Fig. 1 is a vertical transverse sectional view, Fig. 2, a rear elevational view and Fig. 3 a front elevational view, partly broken away, of one embodiment of the invention.

Fig. 4 is a sectional detail view, drawn to an enlarged scale taken on the line IV—IV of Fig. 2 and showing the construction of the flux-gap and the associated moving coil, with its centering and dust-excluding elements.

Fig. 5 is a similarly enlarged sectional detail view, taken on the line V—V of Fig. 2, while Fig. 6 is, likewise, an enlarged sectional detail view, 25 taken on the line VI—VI of Fig. 2.

Fig. 7 is a fragmentary view, to an enlarged scale, of the junction between the permanent magnet centre pole and the front pressing of the magnetic structure, while Figs. 8 and 9 are 30 similar views of modifications falling within the scope of the invention.

Figs. 10 and 11 illustrate two alternative ways of securing the solid centre pole permanent magnet by one of its ends to the associated front pressing of the magnetic structure.

Fig. 12 illustrates one form of screening cap for the exposed rear end of the magnetic flux-gap.

Referring more particularly to Figs. 1, 2 and 3, 40 of the drawings, the loudspeaker shown comprises a combined magnetic structure and sound diaphragm supporting chassis comprising two members 10, 11 constituted by sheet metal pressings or stampings of ferromagnetic material, e. g. of soft iron or mild steel plate, and a short cylindrical barform permanent magnet 12. The latter is desirably of one of the well known directional aluminium/nickel/cobalt alloys of very high coercive force.

The pressing 10 is in the form of a shallow cone or cup and constitutes the supporting means for the conical sound diaphragm 13 of the device. The latter is provided at its apex with the usual cylindrical voice coil former 28 carrying a coil-winding 29 and is secured around its

outer periphery to an annular ring-shaped portion 14 of the pressing 10. Holes 15 provided in the major conical walled part of the pressing serve as back-of-diaphragm sound outlets.

As shown more clearly in Fig. 4 the apical region of the pressing 10 terminates in a planar region 19 having a circular aperture 16 in which is secured, as by flanging-over, a tight fitting bushing 17 also of ferromagnetic metal. This bushing, which is in good magnetic contact with the pressing 10, has an accurate cylindrical bore 18 which constitutes the outer pole-face of the magnetic flux-gap for the moving coil winding 29.

The second pressing 11 serves to span the mouth of the cup-shaped first pressing and has the form of an annular ring 20 whose interior is spanned by two integral diametral arms 21 which intersect at right angles in the centre of the ring. The resultant quadrantal apertures 22 form front-of-diaphragm sound outlets. The annular ring 20 is provided with a series of tapped holes 23 for receiving screws 24 by which such ring is held clamped in intimate contact with the annular rim portion 14 of the pressing 10 so as to provide as low a reluctance path as possible for the magnetic flux which passes across this junction.

The pressing 10 is further provided with a flanged-over outer rim 25 adapted to bear upon the outer surface of the ring 20 with a view to assisting in the accurate location and good magnetic contact of the pressing 10 with respect to the pressing 11. The sound diaphragm 13 is provided with the usual concentric corrugations 27 near to its outer periphery for imparting the required flexibility of mounting and to clear these the diametral arms 21 are stepped forwardly as shown at 26. The plane of the pressing 11, in particular the central region thereof, is one which lies normal to the axis of the conical chassis 10 and diaphragm 13 and hence of the bore 18 of the annular flux-gap 38.

The permanent magnet 12 is mounted endwise upon the rearward face of the pressing 11 at the intersection point of the diametral arms 21 so as to project rearwardly therefrom with its longitudinal, i. e. central axis, normal to the plane of the pressing 11 and precisely coincident with the axis of the bore 18. The rearward and free end of the magnet, which enters into the bore 18, constitutes the inner pole 38 of the magnetic flux-gap 38.

The magnet 12 is in the form of a solid circular section rod. It is provided, near to its free rearward end, with a reduced diameter region 40. This region commences in a plane coincident with that of the forward end of the bushing 17 and extends forwardly therefrom towards the front end of the magnet. The purpose of this reduced diameter region is to increase the permissible tolerance in the alignment accuracy of the moving coil former 28 within the flux-gap 38 and thereby to decrease the risk of contact of the moving coil with the centre pole on account of displacement or misalignment.

The securing of the magnet 12 has to be effected at one end only and, when modern and virtually unmachineable steel alloys are used therefor, without the aid of tapped holes or the like. In the preferred form of the invention this securing is effected by means of adhesive. As seen more clearly from Fig. 7, the front end of the magnet bar is ground truly flat and square, i. e. normal to its longitudinal axis, as at 31. The central zone 32 of the rearward face of the

pressing 11 is similarly finished truly flat and in the required plane so as to form two complementary mating surfaces. These surfaces are then secured together with the aid of a suitable adhesive film 33.

The adhesive employed is preferably one which can be applied in fluid form and in a cold or substantially unheated state. It should set or harden without the aid of any substantial degree of heating, such as would impair or even destroy the magnetic properties of the magnet. A particularly suitable form of adhesive process is that described in British Patent No. 577,823 utilising a thermosetting material and wherein each mating surface is first coated with a heat-hardenable resin such as phenol-formaldehyde condensation product, such coatings being subsequently dried at a temperature below the hardening temperature thereof. A layer of polyamyl acetal powder is then applied between the coated mating surfaces and the parts then held clamped under pressure in a suitable jig while heat to about 160° C. is applied.

The use of plane mating surfaces is not essential and other forms of somewhat less simple character are shown in Figs. 8 and 9. In Fig. 8, the pressing 11 is recessed as shown at 34 to form a socket into which the end of the magnet 12 is arranged to fit snugly while in Fig. 9 the receiving recess is made of frusto-conical form as shown at 35 to receive the correspondingly tapered end 36 of the magnet. In each case 33 denotes the adhesive film.

As an alternative to the use of an adhesive film other fixing methods may be employed. Fig. 10 shows one of these in which the end 41 of the magnet 12 is made a tight force fit into a cylindrical hole 42 in the pressing 11. Before insertion the magnet is provided, by grinding, with an annular groove 43 near to its end and, after insertion into the pressing 11, the relatively soft metal of the latter is swaged or pressed into such groove by the application of suitable tool pressure closely around the hole 42. This pressure application may be made on either or both sides of the pressing 11.

In Fig. 11, the magnet 12 is ground down, as at 49, to provide a spigot-like projection and a seating shoulder. As in the previous example, the soft metal of the pressing 11 is swaged or otherwise deformed so as to grip the virtually unmachineable metal of the magnet. The spigot may be made tapered if desired. In further alternative methods of fixing the solid centre pole magnet, the latter may be force-fitted or fused in position by an electric arc.

The sound diaphragm 13 is secured around its outer periphery to the annular ring-shaped portion 14 by means of adhesive. As shown more clearly in Figs. 5 and 6 the inner region of the portion 14 is relieved as shown at 44 so as to provide a narrow channel for receiving the diaphragm and adhesive. The provision of this relieved region and of similarly relieved regions 65 around the fixing screws 24 and fixing holes 45 ensures that the clamping pressure between the pressings 10 and 11 is developed uniformly over the regions between the fixing screws instead of being localised around such screws. The magnetic reluctance of the junction between the pressings is thereby lowered.

The apical end of the diaphragm 13 and the attached voice coil is accurately centered within the flux-gap 38 by means of a flexible corrugated ring 46 which is secured by its inner periphery to

the junction point between said diaphragm and said former 28. The outer periphery of the centering ring is secured by adhesive to a platform 47 formed in the pressing 10. This platform is appropriately spaced forwardly of the bushing 17 of the flux-gap and lies in a plane disposed normal to the axis of the flux-gap 38.

To prevent ingress of dust and other foreign bodies into the flux-gap, a rear sealing cap 48 of felt or similar porous substance is provided. As shown more clearly in Fig. 4, this cap is arranged to be a snug fit over the projecting rim of the bushing 17 and is either shaped so as to be a snap fit thereon or is secured by adhesive. A spacer 52 disposed between the end of the magnet 12 and the centre of the cap prevents accidental collapse of the latter and consequent fouling of the voice coil. For a similar dust excluding reason the centering ring 46 is preferably of imperforate character while the front quadrantal openings 22 of the pressing 11 are correspondingly covered by a suitable fabric member 50. The latter is secured by adhesive upon the outer face of the pressing 11 and is overlaid around the rim of the latter by the four mounting pads 51 located between the fixing holes 45.

A terminal strip 53 carries terminal lugs 54 connected by way of the usual ligaments to the two ends of the coil winding 29.

A loudspeaker or microphone constructed in the manner described above with its permanent magnet forming the centre pole of the flux-gap and with the soft-iron or equivalent pressings 10, 11 forming the equivalent of a spaced magnetic screen therearound, has the advantage of possessing a negligible external magnetic field. It is, in consequence, eminently suitable for use in close proximity to apparatus, such as a cathode ray tube, which may be seriously affected by such a field. In a television receiver, for example, the scanning raster can be seriously distorted or displaced by even a weak magnetic field.

To reduce still further any small field effects that may occur due to leakage flux around the exposed rear end of the flux-gap 38, the sealing cap 48 may be supplemented or replaced by a member of ferromagnetic material, e. g. fine iron wire gauze. This cap is arranged to fit, in good magnetic contact, upon the bushing 17. Its depth is such that no substantial short-circuiting of the flux-gap 38 is caused thereby. Alternatively the cap may be made of imperforate iron sheet or, more preferably, of sheet metal provided with a number of small holes as shown at 55 in Fig. 12.

As a means of still further augmenting the degree of magnetic screening provided, the fabric member 50 covering the front pressing 11 may be of iron wire gauze and the holes 55 similarly covered.

The invention is not limited to the particular constructions described. For example, in a second embodiment of the invention, the general construction is similar to that already described with the exception that the cylindrical outer flange of the member 10 leads to a further planar fixing plate having a square perimeter. The second member 12 is also of similar square shape and the two members are held together by clamping bolts. In this embodiment, which is particularly adapted for miniature construction, the diametral arms of the second member are not set forwardly, the requisite diaphragm clearance being provided by an inserted spacing ring.

In another embodiment the magnetic structure

comprises a planar front member to which the sound diaphragm is secured and a rear member formed as an arched-shape strip secured at each of its ends to the front member. The outer pole-face of the magnetic flux-gap may be formed by flanging over the edge of the hole in the first member while the two members may be secured together by riveting or spot welding if desired.

I claim:

1. In an electro-acoustic transducer of the moving coil type, a combined magnetic flux structure and sound diaphragm supporting chassis comprising a conical shaped first member of thin sheet ferromagnetic metal having an annular shaped peripheral region, a planar apical region disposed parallel to the plane of said annular peripheral region and a central aperture in said apical region, a bushing of ferromagnetic metal secured in said hole, a substantially planar second member of ferromagnetic metal disposed in the base plane of said first member and having a similar annular shaped peripheral region in contact with that of said first member, a permanent magnet of solid circular section rod form secured by one end only to the central region of said first member and having its opposite end projecting into the bore of said bushing so as to define therewith an annular shaped magnetic flux gap, said magnet rod having a reduced diameter region near to but spaced from the end located within said bushing and a conical sound diaphragm having an axially projecting coil form and associated coil winding at its apex, said diaphragm being disposed entirely within the space defined by said first and second members with its peripheral region secured to said first member adjacent to said annular peripheral region thereof and with said coil form and winding disposed within said magnetic flux-gap.

2. A loudspeaker of the moving coil type comprising a first sheet steel pressing of cupped shape and having an annular peripheral region, a central planar region, an annular shaped platform form around said central planar region and a circular aperture in said central planar region, a second sheet steel pressing spanning the mouth of said first pressing and having an annular peripheral region in intimate contact with said peripheral region of said first pressing, a central imperforate region and a plurality of sound outlet apertures, a short cylindrical bar permanent magnet of aluminum/nickel/cobalt alloy mounted endwise on the inner surface of the central imperforate region of said second pressing with its opposite end projecting into the central aperture of said first steel pressing, a tight-fitting bushing of ferromagnetic metal in said central aperture having a cylindrical bore constituting the outer pole face of an annular flux gap whose inner pole is formed by the free end of said permanent magnet, a generally conical sound diaphragm having its outer periphery secured by adhesive to said first pressing, an axially projecting voice coil at its apex and a flexible centering ring extending outwardly from a region near to its apex, said diaphragm being disposed entirely between said first and second pressings with said voice coil located in said annular flux gap and with said centering ring secured by adhesive to said platform of said first pressing.

3. A loudspeaker as claimed in claim 2 in which said permanent magnet is provided with a reduced diameter region near to but spaced

from its free end to allow increased clearance for the operational movement of the voice coil attached to said sound diaphragm.

4. A loudspeaker as claimed in claim 2 wherein said outer peripheral edge of the diaphragm is received in a recessed or relieved zone of said first pressing to provide for the adjacent unobstructed magnetic contact between the annular peripheral regions of the two members.

5. A loudspeaker as claimed in claim 2 in which said permanent magnet is secured in position solely by means of an adhesive.

6. A loudspeaker as claimed in claim 2 wherein said permanent magnet is secured in position by means of adhesive comprising a thermosetting resinous material.

7. A loudspeaker as claimed in claim 2 wherein said permanent magnet is secured in position by its insertion into a hole within said second pressing and then displacing the relatively soft metal of the latter so as to grip the inserted magnet portion.

8. A loudspeaker as claimed in claim 2 in which said permanent magnet is secured in position by fusing with the aid of an electric arc.

9. A loudspeaker as claimed in claim 2 which includes a screening cap of ferromagnetic material fitted over the exposed rear end of the magnetic flux-gap.

10. A loudspeaker as claimed in claim 2 which includes a screening cap fitted over the exposed rear end of said magnet flux-gap for preventing ingress of dust and other foreign bodies into said flux-gap.
